UNITED STATES PATENT OFFICE.

WILLIAM PRATT, OF GRAND VALLEY, COLORADO.

RAILWAY.

1,112,319.

Specification of Letters Patent. Patented Sept. 29, 1914.

Application filed March 18, 1914. Serial No. 825,526.

To all whom it may concern:

Be it known that I, WILLIAM PRATT, citizen of the United States, residing at Grand Valley, in the county of Garfield and State of Colorado, have invented new and useful Improvements in Railways, of which the following is a specification.

My present invention pertains to metallic sleepers or ties and means for fastening rails thereto; and it consists in the peculiar and advantageous construction hereinafter described and definitely pointed out in the claims appended.

In the drawings accompanying and forming part of this specification: Figure 1 is a plan of a portion of a railway constructed in accordance with my invention. Fig. 2 is an enlarged detail section taken in the plane indicated by the line 2—2 of Fig. 1, and illustrating my novel rail-seating and fastening means. Fig. 3 is a section taken in the plane indicated by the line 3—3 of Fig. 1. Fig. 3^a is a top plan view of one of the rail chairs, showing the transverse corrugations in the depressed seat thereof. Fig. 4 is a detail plan illustrative of a modification hereinafter specifically referred to.

Referring by numeral to the said drawings, and more particularly to Figs. 1 to 3 thereof: 1, 1 are railway rails, which may be and preferably are of conventional type, and 2, 2 are metallic sleepers or ties that are constructed according to my invention. The said sleepers or ties are identical in construction, and therefore a detailed description of the one shown in Figs. 2 and 3 will suffice to impart a definite understanding of all. The sleeper or tie referred to is formed in one piece of steel or any other metal compatible with the purpose of a railway sleeper or tie. It comprises a top wall, side walls and shallow end walls, and is designed to be embedded in ballast, in such manner as to enable the ballast to prevent movement of the tie in the direction of its width. The end walls of the tie are made shallow, as stated, and as indicated by 3 in Fig. 2, in order to brace the sides of the tie and at the same time permit water to pass from below the tie at the ends thereof. In the upper wall of the tie 2 are openings 3^a, which extend throughout the width of the tie, and from the said openings 3^a reduced openings 4 extend toward the ends of the tie, as also toward the middle of the tie, as illustrated. Arranged in the openings 3^a

are rail chairs 5. These chairs 5 are arranged flush with the upper side of the tie, and are provided with tongues 6 designed and adapted to snugly occupy the sub-openings 4, this with a view to precluding movement of the chairs in the direction of the width of the tie, and also with a view to removing any strain attendant on a tendency of the rails to creep from the connecting bolts hereinafter described. It will also be noticed by reference to Fig. 2 that the chairs 5 are provided with depressed seats 7 of a size to snugly receive the bases of the rails.

Arranged under the openings in the top wall of the rail and against said top wall, are reinforcing and anchor plates 8. One of these plates is shown in Figs. 2 and 3, and by reference to Fig. 3, it will be noted that the plates extend the full distance between the side walls of the tie. The plates 8 are connected to the top wall of the tie through the medium of bolts 9, Fig. 1, and the plate 8 and the chair 5 are connected together by bolts 10. It will also be readily observed that the rails are held in their seats and to both the chair 5 and the plate 8 by bolts 11, equipped with heads that overhang the base of the rail.

By virtue of the construction described, the rails are strongly held to the sleepers or ties, and this without the imposition of undue strain upon the connecting bolts. It will also be manifest that when necessary the rail chairs and fastenings may be removed and replaced with new chairs and fastenings, without impairment of the original tie.

In the modified construction shown in Fig. 4, a seat 13 is provided in a chair 5^a and the said chair is arranged in an opening 3^a formed in the upper side of the tie. I would also have it understood that in the modified construction the upper wall of the tie is connected by bolts 9 to a reinforcing anchor plate similar to the plate 8 of Figs. 2 and 3, while the chair is connected to said anchor plate by bolts 10, and the rail is held in the seat 13 by bolts 11, which serve also to connect the chair and the anchor plate together.

Transverse corrugations 17 are provided in the depressed seats 7 of the chairs shown in Figs. 1 to 3 in order to lend additional stiffness and strength thereto, as well as to form strong and durable supports for the rails.

With a view to cushioning the rails and preventing noise as well as to insulate the rails from the ties so that the rails can be used as electric conductors I prefer to interpose cushions 18, of compressed paper or other suitable material, between the chairs 5 and the ties, as indicated by the heavy black lines in Figs. 2 and 3.

Having described my invention, what I claim and desire to secure by Letters Patent, is:

1. In a railway, the combination of a metallic sleeper or tie having a top wall and side walls and also having an opening in its top wall extending throughout its width, an anchor plate arranged between the side walls and under the top wall of the tie and the opening in said top wall, bolts extending through and connecting the top wall of the tie and the anchor plate, a chair snugly occupying the opening in the top wall of the tie and resting flush with the upper side of the tie and having a seat that receives a rail, bolts extending through and connecting the chair and the anchor plate.
2. In a railway, the combination of a rail, a metallic sleeper or tie having a top wall and side wall and also having an opening in said top wall extending throughout the width of the tie and sub-openings extending in opposite directions from said openings and longitudinally of the tie, an anchor plate arranged below the top wall and between the side walls of the tie and also below the opening and sub-openings in said top wall, means connecting the anchor plate to said top wall, a chair snugly occupying the said opening and sub-openings in the top wall of the tie, means connecting the reduced por-

tions or tongues of the chair with the anchor plate, and rail-holding means engaging the base of the rail and connecting the rail chair 45 and the anchor plate.

3. The combination in a railway, of a rail, a sleeper or tie having an opening in its upper side extending throughout its width and also having sub-openings extending in 50 opposite directions from said opening and longitudinally of the tie, and a rail chair receiving the rail and snugly occupying the opening and sub-openings of the tie and arranged flush with the upper side of the tie 55 and connected with the rail and the tie.

4. In a railway, the combination of a metallic sleeper or tie having a top wall and side walls and also having an opening in its top wall extending throughout its width, 60 an anchor plate arranged between the side walls and under the top wall of the tie and the opening in said top wall, bolts extending through and connecting the top wall of the tie and the anchor plate, a chair snugly 65 occupying the opening in the top wall of the tie and resting flush with the upper side of the tie and having a seat that receives a rail; said seat being provided with transverse corrugations, a cushion 70 interposed between the chair and the tie, bolts extending through and connecting the chair and the anchor plate, and rail-holding bolts engaging the rail base and extending through and connecting the chair and the 75 anchor plate.

In testimony whereof I have hereunto set my hand in presence of two subscribing witnesses.

WILLIAM PRATT.
